ATTORNEYS

UNITED STATES PATENT OFFICE.

WHITNEY MERRILL, OF BROOKLYN, NEW YORK, ASSIGNOR TO MERRILL BROTHERS,
OF MASPETH, LONG ISLAND, NEW YORK, A CORPORATION OF NEW YORK.

DROP HAMMER.

Application filed October 16, 1926. Serial No. 142,010.

My invention is directed to the drop hammer lifting roll operating mechanism and comprises a lifting roll operating lever arranged to be engaged by the reciprocating 5 ram in its upward movement with a constant vertical direction of force to raise the lifting roll operating rod and thereby release the roll; whereby side thrust, which so frequently causes breakage of the parts, is eliminated.

My invention more particularly comprises a lifting roll operating lever having an arm provided with a curved under surface arranged to have a lateral shifting engagement with a horizontal upper surface of the ram to not only provide for the constant vertical direction of force but also to increase the relative movement of the lifting roll operating rod to the ram, as the ram 20 slows down.

A practical embodiment of my invention is represented in the accompanying drawings, in which

Fig. 1 represents, in front elevation, that part of a drop hammer which includes my invention.

Fig. 2 represents a horizontal section taken in the plane of the line II—II of Fig. 1, looking in the direction of the arrows.

The vertically reciprocating ram is denoted by 1 and one of the side uprights by 2. The usual lifting roll operating rod is denoted by 3 and the stationary supporting rod 4. An adjustable bracket 5 is clamped to the lifting roll operating rod 3 in any desired position and an adjustable bracket 6 is clamped to the stationary supporting rod 4 in any desired position.

The lifting roll releasing lever comprises 40 an arm 7 clamped to a member 8, pivotally mounted on a stud 9 projecting from the bracket 5, which member 8 is provided with a rigid arm 10, the free end of which is connected by a swinging link 11 to the stationary supporting rod bracket 6.

This arm 7 of the lifting roll releasing lever is preferably somewhat resilient so as to reduce the force of the blow as it is engaged by the upwardly moving ram and it has a curved under surface 12 arranged in position to be engaged by a horizontally disposed upper surface 13 of the ram when

the ram is lifted to a predetermined height. The curved under surface of the arm 7 of the roll releasing lever is arranged to be engaged by the horizontal upper surface of the ram 1 with a constant vertical direction of force to eliminate side thrust between the ram and the lifting roll releasing lever which so frequently causes breakage in those hammers where the lifting lever is engaged by a pin on the ram with a constantly changing direction of force during the engagement of the ram with the lever. The curved under surface of the arm 7 of the roll releasing lever also has a lateral shifting engagement with the horizontal upper surface of the ram, whereby the movement of the lifting roll operating rod is increased relative to the movement of the ram.

What I claim is:—

1. In a drop hammer, a vertically reciprocating ram having a horizontal upper surface and a roll releasing lever having a curved under surface for rocking engagement with said horizontal upper surface of the ram with a constant vertical direction of force, to eliminate side thrust.

2. In a drop hammer, a vertical reciprocating ram having a horizontal upper surface and a roll releasing lever having an arm provided with a curved under surface for rocking engagement with said horizontal upper surface of the ram with a constant vertical direction of force, to eliminate side thrust.

3. In a drop hammer, a vertically reciprocating ram having a horizontal upper surface, a fixed support, a lifting roll operating rod and a roll releasing lever carried by said support and engaging said rod, said lever having a curved under surface for rocking engagement with the horizontal upper surface of the ram with a constant vertical direction of force, to eliminate side thrust, and to increase the relative movement of the roll operating rod to the ram as the engagement shifts laterally toward the axis of the lever.

In testimony, that I claim the foregoing as my invention, I have signed my name this 14th day of October, 1926.

WHITNEY MERRILL.
